(57) **CLAIM**

The ornamental design for a flexible package with integral tab, as shown and described.

DESCRIPTION

FIG. 1 is a perspective view of a flexible package with integral tab showing our new design;

FIG. 2 is a bottom plan view thereof;

FIG. 3 is a top plan view thereof;

FIG. 4 is a side elevational view, the opposite side elevational view being a mirror image thereof;

FIG. 5 is an end elevational view, the opposite end elevational view being a mirror image thereof; and,

FIG. 6 is a perspective view thereof, wherein the tab is in a partially open position.

In FIGS. 1-6, the dashed lines represent end portions of the wrapper for purposes of illustration only, and do not form a part of the claimed design. In FIGS. 1-4 and 6, the dotted lines represent a tearable line of weakness in the wrapper, which forms a part of the claimed design.
